PANEL BOARD

Jonas F. Johnson, Chicago, Ill., assignor of one-half to Fred Degian, Elmhurst, Ill.

Application April 30, 1934, Serial No. 723,039

4 Claims. (Cl. 20—15)

My invention pertains to fabricated composite panel boards of the wall-board type. My board may be used as wall, furniture and door paneling, partitions, wall surfacing, table and counter tops, and the like, and in general as a substitute for wood panels.

Where a wood surface veneer is carried on a soft fibre backing such as a pressed bagasse board, there is ordinarily danger of the veneer cracking and pulling apart when subject to dry air, or penetrated by nails, of warping when damp, and of being dented into the soft backing. One object of my invention is to avoid or lessen these dangers. This I accomplish by a metal sheet between the veneer and backing.

A further object is to adhere these three elements—the backing, the metal sheet and the veneer—together firmly and permanently, overcoming the problem of making an adhesive hold to a metal surface. I solve this problem by adhering the veneer directly to the fibre board through perforations in the intervening metal sheet.

My resulting panel board has many advantageous features. It is light in weight because the fibre backing is light and the veneer and metal sheet add little weight per square foot. It has a higher tensile strength in all directions of its plane, because of the reinforcing effect of the metal sheet. The veneer and metal sheet greatly increase the general strength and rigidity of the composite board over that of the bagasse board backing, but under an extreme bending force these reinforcing layers will flex before the panel will break. The metal sheet and veneer also tend to prevent warping of the complete panel. Despite the thinness of the surface veneer of wood, it may be nailed close to the edges without danger of splitting either the veneer or the backing, this because of the intimate securing of the reinforcing metal sheet thereto. It may present a real, and not an imitation, wood surface but the wood veneer is protected against ill effects of either excessive moisture or dryness, because of the reinforcing effect of the metal sheet. My panel retains the heat insulating function of the bagasse board backing, and to this is added that of the wood veneer. It also retains the sound insulating property of the backing. The fire resistance of my panel is increased by the metal sheet over that of the slow-burning fibre backing; and if desired the fire resistance may be further increased by a supplemental sheet of asbestos. The metal sheet will conduct away and dissipate localized appli-

cations of extreme heat such, for example, as might result from a short circuit in electric wiring, and this will tend to prevent fires. My panel readily lends itself to a double-surfaced panel where the fibre backing becomes a core between two veneer sheets and metal sheets, which may economically be used for partitions, door panels, and the like. My panel is economical to manufacture.

The foregoing, together with further objects, features and advantages of my invention are set forth in the following description of specific embodiments thereof which are illustrated in the accompanying drawing, wherein:

Fig. 1 is a perspective view of a fragment of my single-surfaced panel;

Fig. 2 is an "exploded" perspective view thereof;

Fig. 3 is a cross-section taken on the line 3—3 of Fig. 1;

Fig. 4 is a perspective view of a fragment of a modified form of paneling where the metal sheet is within the backing board;

Fig. 5 is a similar view of another modification having an auxiliary layer of sheet asbestos; and

Fig. 6 is a similar view of double-surfaced panel.

Referring first to the form of Figs. 1, 2 and 3, my panel board 10, which it will be understood is factory assembled and shipped in convenient standard sizes, comprises three major layers. Each layer is self-contained and pre-formed and preferably cut to the standard size of the resulting panel before assembly. The first layer is a main body or backing 11 which may be a pressed bagasse board such as manufactured by the Celotex Company of Chicago, under the trademark Celotex, or a wood fibre board such as is made from steam-explored yellow pine chips pressed into sheet board form as, for example, is manufactured by The Masonite Corporation of Chicago under the trade-mark Masonite, or cork board or any other of the many known types of light insulating boards of relatively soft fibrous material. I contemplate however that for certain purposes a backing of the plaster-board or plywood types may be substituted.

The second or intermediate layer is a perforated metal sheet 12 which will later be described.

The third or outer layer normally provides the exposed surface for the composite panel board. It is preferably a thin veneer 13 of virgin wood (as distinguished from a sheet of comminuted or composition wood).

I contemplate that other suitable materials may

be either substituted for the wood veneer or applied to its outer surface to meet specific requirements or give desired effects, as for example, linoleum or rubber flooring, for bathroom walls 5 or card table tops or counter tops and marbleized linoleum for store or counter fixtures. Where leather, canvas, ornamental fabrics or other relatively limp or plastic surfacing is desired for decorative effect, they are preferably applied to 10 the outer surface of the veneer, which may be done before assembly, or after assembly or after the panel is installed.

Referring again to the metal sheet 12, I prefer to use thin rolled sheet steel having overall 15 stamped-out perforations 14. In a typical panel board having a backing sheet 11 of say $\frac{3}{8}$ inch thickness and a hard wood veneer 13 of $\frac{1}{32}$ inch thickness, the metal sheet may be 24 to 28 gauge. 20 A layer of adhesive 15 such as glue or adhesive cement is applied preferably both to the inner surface of the veneer 13 and the outer surface of the backing 11. The backing and veneer are then superposed with the metal sheet between 25 them and the assembly is put in a press or passed between rollers. This compression causes the layers to adhere together and also forces the adhesive into the perforations.

If the adhesive be applied directly only to the 30 backing, some of the adhesive is forced through the perforations and into contact with the veneer in the areas opposite the respective perforations. Also to a certain extent the adhesive flows between the lands of the metal sheet and the inner 35 surface of the veneer and away from each perforation, to increase the area of contact of the adhesive with the veneer, in addition to the aggregate area of the perforations.

If the adhesive be applied directly only to the 40 veneer, it will similarly be forced through the perforations into contact with the backing. Whichever of these three methods is followed, the 45 perforations will be permanently filled by the adhesive. When the adhesive contracts upon setting it will thereby tend to pull the veneer and backing more firmly together with the metal sheet therebetween.

While I contemplate that there will preferably be a direct surface-to-surface cementing of the 50 metal sheet to the backing board and to the veneer, I recognize that it is difficult to get a good adherence to a metal surface. The direct adherence of the veneer to the backing by the adhesive through the perforations provides a firm 55 permanent assembly which does not depend upon the less reliable adhesion to the surface of the metal.

I have previously mentioned that the glue or other adhesive upon setting and drying will contract to pull the veneer and the backing together 60 transversely of the plane of the panel. A slight transverse deformation of the backing and veneer is indicated in the cross-section of Fig. 3. But the contraction of the glue upon drying is 65 not only transversely of the plane of the panel, but also in the plane of the panel. Thus the slug of glue which occupies each perforation, upon drying, will contract to pull itself away from the margins of the perforations, leaving a slight annular space 70 which affords a certain amount of play in the plane of the panel. There are situations where the wood veneer will tend to expand under moisture or the backing will tend to expand under moisture or under heat the wood 75 will tend to dry while the metal expands. These

conditions within the limits of an ordinary panel will not be great. But in the event they do occur and there is a shearing of the surface adherence of the glue which binds the metal to the backing or the metal to the veneer, such surface 5 adherence may be ruptured without freeing the assembly. This causes a certain amount of shifting of the metal sheet relative to the backing and the veneer, which is permitted by the annular spaces between the glue slugs and the 10 perforations.

In Fig. 6, I have illustrated a double-surfaced panel where the metal sheet and veneer are applied to both sides of the backing board, which then becomes a core. This is particularly 15 adapted for use as a partition, door panel, or the like.

Fig. 4 shows a modification where the veneer is directly adhered to the outer surface of the 20 backing board and the metal sheet is inserted between, and adhered to the inner surfaces of, two plies of the backing board. If desired, a veneer may be applied also to the exposed back 25 surface of the backing board to provide a double-surfaced panel.

In the modification of Fig. 5, I have included a 30 layer of sheet asbestos 16 which is inserted either between the metal sheet and the backing board or, as specifically illustrated, between the metal plate and the veneer. In the latter case, the 35 veneer is directly adhered to the asbestos sheet. Such a modification may be used when greater fire resistance is desired.

I claim:

1. As an article of manufacture, a composite 35 panel handleable as a unit and comprising a pre-formed backing of stiff compressible fibre board, a pre-formed surfacing veneer of virgin wood, a pre-formed metal sheet, wholly confined between the planes of its own surfaces, interposed 40 immediately between the board and the veneer and in surface contact therewith, overall perforations in the metal sheet, and an adhesive adhering to the juxtaposed surfaces of the board and of the veneer and extending therebetween 45 through the perforations for holding the board, metal sheet and veneer in permanently assembled fixed relation as a unitary panel, the inner surface of the veneer at the perforations being substantially co-planar with the inner surface there- 50 of between the perforations.

2. A double-surfaced composite panel of the 55 wall-board type comprising a core layer of stiff compressible fibre board, an exposed surfacing sheet of wood veneer at each side of the core, an all-over perforated metal sheet between and in surface contact with the core layer and each 60 of said veneer sheets, and an adhesive adhering to an outer surface of the core and to the inner surfaces of the respective veneer sheets and extending through the perforations in the metal sheet for permanently holding the veneer sheets 65 to the core with the metal sheets therebetween.

3. A composite panel of the wall-board type 70 comprising a backing of stiff, compressible fibre board, a second layer of self-supporting sheet material, a layer of perforated flat metal, wholly confined between the planes of its own surfaces, coextensive with the panel and intermediate, and in surface contact with, the fibre board 75 and the second layer, and an adhesive applied only to the backing sheet extending through the perforations in the metal layer and directly adhering the fibre board to the second layer.

4. As an article of manufacture, a composite 75

panel handleable as a unit and comprising a pre-formed backing of stiff compressible fibre board of a thickness of the order of $\frac{3}{8}$ ", a pre-formed surfacing veneer of virgin wood of thickness of the order of $\frac{3}{16}$ ", a metal sheet of thickness of the order of 26 gage, wholly confined between the planes of its own surfaces, interposed immediately between the board and the veneer and in surface contact therewith, pre-formed with over-
5 all perforations in the metal sheet, and an ad-
hesive adhering to the juxtaposed surfaces of the board and of the veneer and extending there-between through the perforations for holding the board, metal sheet and veneer in permanently as-
sembled fixed relation as a unitary panel, the 5
inner surface of the veneer at the perforations being substantially co-planar with the inner sur-
face thereof between the perforations.
10
